UNITED STATES PATENT OFFICE.

GEORGE J. BURNS, OF YOUNGSTOWN, OHIO.

THERMAL GASIFYING MOTOR CONSTRUCTION.

Application filed January 30, 1922. Serial No. 532,923.

This invention relates to a new motor construction, more particularly to a construction of internal combustion engine embodying means to obtain a better and more adequate cooling of the motor, an increased efficiency of the fuel charge and better lubrication than possible in ordinary motor construction.

To that end the present invention is based on certain fundamental factors that enter into the successful operation of the invention. One of the primary objects of the invention is to provide a construction which may be in the form of a crown for the motor bloc or otherwise which effectually cools the engine, reduces the temperature in the crank case and at the same time supplies heat and moisture for the purpose of obtaining the increased efficiency of the fuel charge.

The above mentioned general objects of the invention involve certain fundamentals upon which the invention to a large extent relies. In explanation of those fundamentals, the following observations are to be noted, to wit:—The action of heat alone on fuel to be used for combustion purposes is not adequate in the process of breaking up the molecular construction of the fuel. Therefore, the present invention involves the incorporation of moisture with the fuel charge whereby the skin of the molecules will be caused to swell rendering the same susceptible to air friction and to breaking up, making a true gas for the combustion.

In that connection it is well known that the ordinary mixing devices and carburetors in general use supply the fuel in atomized particles, as a mist, as distinguished from a liquid completely broken up into a true gas as is provided for by the present invention. In its application to air cooled motors the invention possesses special utility inasmuch as it presents a construction which permits the use of the fuel as a cooling medium for the motor and at the same time operates to heat the fuel for use in the process of generating the gas for explosion, thus obviating the serious defects incident to the operation of the ordinary air cooled motors. Thus it will be seen that it is the intent and object of the present invention to provide an improvement in motor construction involving the carrying out of a process of making a true gas and lowering the heat in the motor cylinder where the friction heat is usually excessively developed, thus preventing the

oil in the crank case from becoming unduly thinned from unexploded gas and by the excessive frictional heat. Carbon deposits will therefore be eliminated and the so-called pre-ignition will be prevented.

Another important object of the invention is to introduce means of a suitable character, such for example as a fan, in the crank case of the motor so that such means or fan will assist circulating the vapors, and the air taken in through the breather pipe or from another source against the metal parts and walls serving to reduce the temperature and therefore cool the oil, thus conserving and preserving the lubricant qualities of the oil to the maximum degree. At the same time the means or fan referred to may be of such a nature as to operate under the influence of the suction of the motor and thereby assist in directing the crank case gases to the fuel supply. Furthermore, the means or fan referred to operates to circulate the crank case gases in such a manner as to not interfere or mix with the solid or body parts of the lubricant which are thrown up into the cylinders for lubrication, thus permitting the lubricant to thoroughly pack into the lubricant receiving parts of the motor; also the said means or fan is intended effectually to prevent anything but gas to enter the suction line.

In carrying forward these general objects, involving the fundamental principles referred to, the invention contemplates as one of its specific objects the embodiment of the invention in what may be termed as a thermal gasifying crown for the motor, that is to say, a so-called removable head having the capacity for using the fuel as a cooling medium and also involving means for gasifying the fuel and incorporating with it the moisture and the gases from the crank case, producing the true highly explosive gas.

In carrying out the invention the same is necessarily susceptible of embodiment in various forms of construction without departing from the spirit or principle thereof, but in order to illustrate the particular features claimed one example is shown in the accompanying drawings in which

Figure 1 is a side elevation of a motor equipped with the novel crown proposed by the present invention.

Figure 2 is a vertical cross-sectional view taken on the line 2—2 of Figure 1.

Figure 3 is a diagram showing the appli-

cation of the invention in connection with a motor for using the heavier hydrocarbon fuels, such as kerosene.

Similar reference characters designate corresponding parts throughout the several figures of the drawings.

As above pointed out the invention may be embodied in different forms of construction and the arrangement of parts may be varied in many ways without departing from the intent and object of the invention, but as the essential and vital features are present in the form of construction illustrated as the example in the drawings, a particular description of that example will now be given. Referring thereto, it will be observed that B designates the motor bloc having the usual exhaust valves E and intake valves I and provided with the liquid circulating jacket W and the intake passages P communicating with the intake valves I, while the exhaust valves E control the exhaust through the usual exhaust manifold E' as will be seen from Figure 2.

In the construction shown the novel crown or head C takes the place of the so-called motor head which may or may not be removable, but in the illustrated form of the present invention the said crown or head is shown as being removably held in place by bolts located at suitable and convenient points. A distinctive feature of this crown or head construction is the same being provided with an interior gasifying chamber designated by the numeral 1. This chamber has projecting therein a plurality of baffle members 2, (preferably hollow) arranged in relatively staggered relation or otherwise to provide means for baffling or arresting the fuel while it is in the process of being broken up and gasified in the chamber, and it is within this chamber that the moisture in the atmosphere is utilized for swelling the molecular particles and rendering them susceptible to the breaking down action of air and heat friction. The said baffle members project from the top and bottom walls 3 and 4 of the chamber 1, which extends transversely through the intermediate portion of the crown and communicates at one side with the fuel intake pipe 5 from the carburetor. The opposite side of the chamber communicates by means of the passages 6 with the intake passages P in the motor bloc thereby to establish communication between the fuel intake pipe 5 and the intake valves I.

The interior of the crown at opposite sides of the walls 3 and 4, which form the chamber 1, is provided with the liquid circulating jacket J which communicates at convenient points, as through the passage-way 7 with the liquid jacket W of the motor bloc. Thus, the liquid which circulates about the cylinders also freely circulates in the crown about and around the chamber 1 in which

the fuel vapor passes on its way to the intake valves. Also as shown in Figure 2 the crown C is provided with openings for receiving the spark plugs S in the usual manner.

It will now be seen that the gasifying chamber 1 in the crown receives the atomized fuel from the carburetor through the pipe 5 and also receives the gases from the crank case through the pipe 8 which is connected with the offset or recess R in the crank case which houses the circulating fan F, which is exposed to the interior of the crank case but presents no projection beyond the line of the inside walls of the case. The said fan F operates to circulate the vapors in the crank case and the air taken in through the breather pipe or other source thereby serving to reduce the temperature within the crank case and cooling the lubricating oil. By preserving a more normal temperature for the oil, the lubricating qualities thereof are conserved. That is to say, by preserving a safe temperature within the crank case the lubricating oil is not distilled into its finer constituents which possess little or no lubricating qualities while at the same time the circulation of atmospheric air due to the suction in the pipe 8 and fan F serves to also remove any of the fuel gas which escapes the pistons on the compression stroke and further prevents the disintegration of the oil from that cause. As the fan is located in the recess R and has no projection into the crank case, it in no way interferes with the circulation of the oil to properly lubricate the moving parts of the motor while at the same time it serves more or less as a screen to prevent oil being thrown up into the pipe 8 by the splash from the crank shaft which is very considerable at high speeds.

Also means is provided for admitting atmospheric air into the said gasifying chamber and while that may be done in various ways a convenient and practical means of accomplishing that result is suggested in the drawings, namely to provide the fuel pipe 5 with an air intake valve 9. Therefore, the relatively cool atmospheric air entering the gasifying chamber and impinging on the walls thereof to generate moisture due to condensation and that becomes incorporated with the incoming atomized fuel from the carburetor and with the gases from the crank case. This mixture by the heat in the gasifying chamber becomes converted into a highly explosive gas, and, as heretofore pointed out, this desirable result is facilitated by the moisture or water radical producing the breaking up of the molecular construction of the fuel so that it will be completely converted into the gaseous state. That is to say, the liquid cooled chamber 1 prevents excessive heat generated by the operation of the motor from evaporating the

requisite moisture in the charge to insure its efficiency and as a matter of fact serves to condense the moisture taken in from the outside air and also from the gas in the crank case thereby to insure an adequate degree of moisture in the heater mixture.

While the present device is particularly adapted to thoroughly gasify the fuel charge to be used in the engine, and at the same time pre-heating the same without over-heating, nevertheless the construction may also be used for pre-heating and gasifying relatively heavy fuel oils such as kerosene and the like which are especially adapted for use in connection with motors for tractors and other heavy duty work. That is to say, instead of the intermediate chamber 1' of Figure 3 being used to conduct the vapors to the inlet valves of the motor, it preferably communicates with a source of fuel supply S' by means of the pipe 10. After the fuel oil has been thus pre-heated in the chamber 1^a it may be conveyed by the pipe 11 to the carbureting device 12 to be atomized and supplied to the intake manifold of the motor in the usual manner. Thus, we have a construction wherein the fuel, such as kerosene, is employed as both the cooling medium in the jacket of the device and also as the fuel for the motor and this feature is particularly valuable in connection with air cooled motors.

It is a well known fact that tractor motors by reason of their heavier construction develop a very high degree of heat and while a water cooling system is utilized to reduce this heat, nevertheless an additional cooling

effect may also be obtained by passing a normally cool fuel oil through the pre-heating chamber 1. As previously explained the 40 temperature of this chamber is considerably less than the firing heat of the fuel and it is therefore, relatively speaking, cool. Nevertheless, the fuel in passing through the chamber 1' absorbs some heat which has the 45 advantage of raising its temperature while at the same time absorbing heat from the circulating system, thereby obtaining the desirable effect of preliminarily pre-heating the fuel and cooling the motor simultaneously. 50

Without further description it is thought that the features and advantages of the present improvement will be readily apparent, and it will of course be understood that 55 changes in the form, proportion and minor details of construction may be resorted to without departing from the spirit of the invention or scope of the appended claim.

I claim:

A removable vaporizing head for internal combustion engines having inlet and outlet openings at opposite sides thereof, and the said head consisting of an intermediate tortuous hollow wall portion establishing communication between said openings, and said tortuous wall portion being surrounded with water receiving spaces whereby when the head is fitted to the motor bloc water from the water jacket thereof will circulate about 70 said tortuous wall.

In testimony whereof I hereunto affix my signature.

GEORGE J. BURNS.
